LATCH

Gordon E. Roedding, Grand Rapids, Mich., assignor to Grand Rapids Brass Company, Grand Rapids, Mich., a corporation of Michigan

Application January 7, 1939, Serial No. 249,683

5 Claims. (Cl. 292—165)

The present invention relates to latches for the door closures of refrigerators and the like; and its object, generally, is to provide improved means for operating such latches, i. e., for re-

tracting the latching bolts thereof, which means may be readily operated by manual movements in various different directions; and more particularly, to provide improved mechanism for thus operating such latches.

10 This and any other and more specific objects hereinafter appearing are attained by, and the invention finds preferable embodiment in, the illustrative latch structure particularly described in the body of this specification and illustrated by the accompanying drawings, in which:

Figure 1 is a front view of a latch structure mounted on a door closure;

Figure 2 is a vertical sectional view thereof (enlarged) taken on line 2—2 of Figure 1;

20 Figure 3 is a vertical sectional view of the same taken on line 3—3 of Figure 2;

Figure 4 is a horizontal sectional view thereof taken on line 4—4 of Figure 2;

Figure 5 is a like sectional view of certain portions of the same but showing the parts in a different position;

Figure 6 is a vertical sectional view of portions of the same, similar to Figure 2 but showing the parts in a different position;

30 Figure 7 is a vertical sectional view thereof, similar to Figure 6 but showing said parts in another different position;

Figure 8 is a vertical sectional view of portions of the same taken on line 8—8 of Figure 7.

35 The latch structure illustrated by these drawings includes a preferable form of my means for operating a latch (i. e., for retracting its latching bolt) and also one particular type of latch illustrating its operation by said means.

40 The latching bolt 1 of this latch is slidable, outwardly for operatively engaging its keeper 2 on the door jamb 3 as shown in Figure 4 and reversely for retracting the bolt as shown in Figure 5, by means of a toggle comprising the 45 arms 4, 5 connected by a pin 6 turnable and slideable in the slot bearing 7 of arm 5 (as best seen in Figure 5), these arms respectively being pivoted at 8 on the latch bolt and at 9 on the sides 10 of the latch's casing 11 mounted in the door closure 12.

45 A spring 13 pressing the rearward extension 14 of the bottom 15 of arm 5 urges the toggle to its position shown in Figure 4. Between the guides 16 of the casing's sides, a slide 17 is movable, 55 this slide having means—its projections 18 en-

gaging the flanges 19 of the toggle arm 5—for turning this arm outwardly to break the toggle by the movement of the slide toward its position seen in Figure 5.

A stiff spring 20 pressing between the bottom 5 of arm 5 and the pin 6 serves to hold the toggle in its unbroken position when the closure is slammed shut and the extremity of the latch bolt rides up on the keeper's incline 21.

10 My means for retracting the latch bolt comprises an operating lever handle turnable as hereinafter described, and means operatively intermediate this lever handle and connected with the bolt for retracting the same by the lever handle's turning movement. In the illustrated embodiment of the invention, the operating lever 22 has an outer handle arm 23, an inner arm 24 and a medial ball portion 25 turnably bearing in an annular ball-bearing socket member 26 seated in the cylindrical recess 27 in the inner side of 20 the lever handle's mounting plate 28 through which the lever extends.

15 This ball portion has an opening extending horizontally therethrough with elongated parallel side walls 29 as shown in Figures 2, 6 and 7, 25 and end walls 30 which diverge outwardly from the ball portion's center as best seen in Figure 3. A fulcrum pin 31, mounted at its ends in openings in the opposite sides of the socket member and of the recess, extends diametrically, horizontally through the ball portion's said opening, this pin bearing turnably and slidably on the opening's walls in the various turning movements of the lever handle.

20 The inner arm 24 of this lever handle has at 35 its opposite sides respectively a pair of bearings, preferably the anti-friction rollers 33, 33¹ turnable on the ends of a spindle 34 extending through said arm; and the illustrated means for retracting the latch bolt comprises also a lever element 40 35 fulcrumed at 36 on whose lower arm 37, which is pressed inwardly by a spring 38, is pivoted a short rod 39 extending through an opening 40 in the slide 17 and having shoulders 41, 41¹ adapted to engage the slide for moving the same. 45

25 The other (the upper) arm 42 of this lever 35 has a bearing surface or cam 43 on which bear both or either of the rollers in the operating lever's turning movements, as hereinafter explained. This cam surface is inclined, as illustrated, relatively to the arcual direction of the movement of the upper arms 42 (i. e. the rollers) when moved by the turning of the lever handle.

30 It will be seen that the operating lever is so mounted that by drawing its handle outer arm 55

23 outwardly from the face of the closure both rollers will be made to ride up on the inclined cam surface 43 of lever 35 and thus turn this lever from its normal or rest position seen in 5 Figure 2 toward the position shown in Figure 6, thus moving the slide 17 outwardly for breaking the toggle and retracting the latch bolt; or the lever handle may be turned either way parallelly with the closure so that one or the other roller 10 (as the case may be) will be made to ride up on said inclined surface or cam as shown in Figure 7 thus moving the slide outwardly for breaking the toggle and retracting the latch bolt. In this Figure 7 the lever handle's arm 23 is shown 15 turned parallelly with the closure and toward the viewer, thus causing the roller 33 to thus ride up on the cam surface 43, the other roller 33¹ merely idling.

The invention being intended to be pointed out 20 in the claims, is not to be limited to or by details of construction of the particular embodiment thereof illustrated by the drawings or hereinbefore described.

I claim:

25 1. A means for operating a latch bolt, comprising: a ball socket having a diametrical fulcrum pin; an operating lever handle having a ball portion turnably bearing in the socket, said portion having an opening therethrough with 30 parallel side walls and end walls diverging outwardly from said portion's center, in which opening the fulcrum pin bears; and a pivotally mounted unitary element operative intermediate the lever handle and the latch bolt turnable for re- 35 tracting the latch bolt by the turning movement of the handle.

2. A means for operating a latch bolt, comprising: an operating lever handle fulcrumed for opposite turning movements and turning movement at right angles thereto, and having rollers 40 at its opposite sides respectively; and a lever connected with the latch bolt and having a cam, both rollers bearing on the cam in the handle lever's last mentioned turning movement and the

rollers respectively bearing on the cam in the lever handle's opposite turning movements respectively, for retracting the latch bolt.

3. A means for operating a latch bolt, comprising: an operating lever handle fulcrumed for opposite turning movements and turning movement at right angles thereto, having a pair of bearings at its opposite sides respectively; and an element mounted for movement relatively to the lever handle, connected with the latch bolt and 10 having a cam, both of said bearings bearing on the cam in the lever handle's last-mentioned turning movement and said bearings respectively bearing on the cam in the lever handle's opposite turning movements respectively, for retracting 15 the latch bolt.

4. A means for operating a latch bolt, comprising: an operating handle mounted for opposite turning movements and turning movement 20 at right angles thereto, having laterally spaced bearings; and an element mounted for turning movement relatively to the handle, connected with the latch bolt and having a cam, both of said bearings bearing on the cam in the handle's last-mentioned turning movement and said bearings 25 respectively bearing on the cam in the handle's opposite turning movements respectively.

5. A means for operating a latch bolt, comprising: an operating lever fulcrumed medially thereof for opposite turning movements and 30 turning movement at right angles thereto, having a handle arm and an arm with bearings at its opposite sides respectively; and a lever element fulcrumed for turning movement parallelly with the operating lever's last-mentioned movement, said lever element being operatively connected with the latch bolt and having a cam arm, both of the operating lever's bearings bearing on the cam arm in the operating lever's last- 35 mentioned turning movement and said bearings alternately bearing on the cam arm in the operating lever's said opposite turning movements respectively, for retracting the latch bolt.

GORDON E. ROEDDING.
